UNITED STATES PATENT OFFICE.

WILLIAM B. NEWLON, OF FREMONT, NEBRASKA, ASSIGNOR OF ONE-HALF TO GEORGE A. MEAD, OF CENTRAL CITY, NEBRASKA.

FEED-REGULATOR.

1,233,110.

Specification of Letters Patent. Patented July 10, 1917.

Application filed April 30, 1914. Serial No. 835,405.

To all whom it may concern:

Be it known that I, WILLIAM B. NEWLON, a citizen of the United States, and resident of Fremont, in the county of Dodge and 5 State of Nebraska, have invented certain new and useful Improvements in Feed-Regulators, of which the following is a specification.

This invention relates to means for sup- 10 plying ingredients to a mixture.

It is especially adapted for use in the man- ufacture of cattle feeds wherein molasses or other liquid is mixed with alfalfa or other meal. It is to be understood, however, 15 that the use of the invention is not limited to such application. On the contrary it might be advantageously employed in the mixing of concrete or cement or in a multi- tude of other uses.

20 The object of the invention is to provide a means of the character described whereby the ingredients are efficiently and accurately supplied in the desired proportions. Other and ancillary objects of the invention will 25 appear hereinafter.

In the accompanying drawings, which illustrate the invention,

Figure 1 is a side elevation of apparatus embodying the invention;

30 Fig. 2 is a side elevation of the apparatus of Fig. 1, but viewed from the opposite side;

Fig. 3 is an end view of the apparatus viewed as indicated by the arrow *a* of Fig. 1;

35 Fig. 4 is an elevation of the other end of the apparatus;

Fig. 5 is a longitudinal section on the line 5-5 of Fig. 4;

Fig. 6 is a side elevation of a portion of 40 the tripping means, as will be hereinafter referred to;

Fig. 7 is an end view of the same, looking in the direction of the arrow of Fig. 6;

Fig. 8 is a top plan view of the same;

45 Fig. 9 is an elevation of a latching means for securing a clutch member, as will be hereinafter explained;

Fig. 10 is a side elevation of the apparatus shown in Fig. 9;

50 Fig. 11 is a detail view of a portion of an exit valve of one of the receptacles;

Fig. 12 is a detail view of a valve securing and guiding means;

55 Fig. 13 is a detail, showing the arrangement of valves and valve operating means;

Fig. 14 is an enlarged view, illustrating the relative formation and location of a roller and cam, as will be hereinafter referred to; and

Fig. 15 is a view on an enlarged scale, of 60 a device for completing the movement of and holding the material feeding means.

Fig. 16 is a fragmentary view similar to Fig. 5 showing in enlarged detail the inlet valve for the receptacles;

Fig. 17 is an end view of the apparatus of Fig. 16 looking in the direction of the arrow;

Fig. 18 is a view similar to Fig. 16, of 70 the exit valves of the receptacles; and

Fig. 19 is a section on the line 19-19 of Fig. 18.

The detail views, Figs. 7 to 13 inclusive, 75 are drawn on a larger scale than the other figures.

Referring to the drawings, the granular material or meal is placed in the hopper A. From this hopper the granular material is fed into boxes or receptacles B and C, which are controlled by inlet and outlet valves. 80 These boxes may move up and down, the weight of the material tending to force them downwardly, while suitable means, as the weight arms D and E tend to force the boxes upwardly.

85 As a box is fed with material from the hopper, it will sink, as the material in the box overcomes the weight arm, and will abut against a mechanism F which will then operate to unlatch a clutch G. The clutch will then move into engagement and cause the driving of the shaft H through the gears I from the shaft K, which is continuously driven by suitable means, as the pulley wheel L.

90 From the shaft H extends a lever mechanism M which drives the inlet and exit valves of the boxes or receptacles B and C.

To supply the fluid ingredient, such as 100 molasses, a pump N is provided, having the supply pipe O and delivery pipe P. This pump is driven from the shaft H, which operates the inlet and outlet valves. The apparatus referred to is mounted in a suitable frame R.

105 The operation of the apparatus may be briefly reviewed as follows:

A given receptacle having its inlet valve open and its exit valve closed, the meal will pour in from the hopper until it over-

comes the opposed weight arm. The box will then sink and permit the pump and valve operating shaft to be thrown into driving relation to the pulley. The counter-shaft from which the valves and pumps are driven will then make one-half a revolution (devices being provided for so limiting its movement, as will be hereinafter described). This movement will suffice to close the inlet valve of the sunken receptacle and open its exit valve when its charge will be precipitated into a suitable mixing receptacle, which is also adapted to receive the molasses delivered by the pump. The box which received the material from the hopper, having been relieved of its weight, will rise. The amount of material contained in the box at which it will sink may be adjusted by adjusting the weight on the arm. At the same time that the inlet valve of one of the receptacles was closed, as just referred to, the inlet valve of the other was opened and the opening of the exit valve of the first will be accompanied by a closing of the exit valve of the other, so that while the sunken receptacle is discharging its contents, the other is being filled, and will, in its turn, sink, and set in operation the valve operating means and the pump, as described. There is thus an alternate filling and emptying of the two receptacles, the emptying of each occurring upon a predetermined amount of material fed into it, and such emptying is accompanied by the delivery of a predetermined amount of liquid supplied by the pump. The operation thus goes on indefinitely, without the intervention of any manual operation, the operations of the liquid and granular feeding means being dependent upon each other, so that proper relative operation, timing and proportioning of the mixture is assured.

Referring now to the apparatus of the drawings, more in detail, the receptacles B and C may each move up and down, being guided in their movement by anti-friction wheels 1 and 2 respectively at their corners. The receptacles are suspended by means of links 3 and 4, these links being on opposite sides of their respective receptacles. In the case of receptacle C, the links 4 are pivoted at their lower ends to the receptacle near its bottom and at their upper ends are pivoted to the bifurcated or Y-shaped lever 5 pivoted to the frame at 6, the non-bifurcated arm having a weight 7 which counterbalances the receptacle C and its contents, the amount of material at which the receptacle will lower being adjustable by means of the shifting of the weight 7 along the arm. Similarly the receptacle B has its supporting links 4 pivoted to its lower end and to the bifurcated lever 8 having the weight arm upon which is the weight 9. Tubes or sleeves 10 and 11 extend down-

wardly from the hopper A and telescope within the upper ends of the receptacles B and C. The material for the hopper is thus always directed into the receptacles without spilling, and relative up and down movement of the receptacles with relation to the hopper is permitted.

The inlet of material from the hopper into the receptacle is controlled by means of a valve 12 which slides over the upper ends 70 of the sleeves 10 and 11. In the structure shown, a single valve 12 is employed to control the inlet to both receptacles, this valve sliding on angle irons as 12^a and 12^b secured to the frame. When the valve is moved to 80 open the inlet to the receptacle B, it closes the inlet to the receptacle C and vice versa. The exit of material from receptacles B and C is controlled by two valves 13 and 14 connected together by a rod 15 which at each of 85 its ends is pivoted to one of the valves. The valves 13 and 14 form substantially the bottoms of their respective receptacles and are carried on guides formed of angle irons, one pair on each receptacle on opposite sides 90 thereof, as 13^a and 13^b on receptacle C. These angle irons extend across the bottom of the receptacle and each has one side secured to the bottom of the receptacle, the other side of each of the angle irons extending 95 inwardly beneath the receptacle and forming a guide for the support of the valve. The manner in which the valve is supported on the angle iron is shown clearly in Figs. 12 and 19, from which it will be 100 seen that the valve slides on the bottom of the angle iron and is supported by bent up portions 16 which overlap the angle iron. These angle irons extend, not only across the receptacle, but extend to one side of the 105 receptacle a sufficient distance to afford supports for the valve when it has been slid out from beneath the bottom of the receptacle to open the exit.

Both of the receptacles discharge into the 110 chute 17.

The inlet and exit valves of the receptacle are operated by a link mechanism as follows:—To the gear 18 upon the shaft H is pivoted at one end a driving rod 19. At its other end this driving rod is pivoted to a link 20. This link 20 is also pivoted to the frame at 21. Also pivoted to the link 20 at 22 is a link 23. This link 23 is also pivoted at 24 to the lever 25 which is pivoted to 115 the frame at 26. At its lower end the lever 25 is pivoted to the link 27, which in turn is pivoted to the valve 13 at 28. With the arrangement of pivots as described, it will be apparent that the valves 13 and 14 are 120 always connected together by the rod 15, so as to be moved together, the one into exit closing position when the other is moved into exit opening position, and that these valves may be operated at any time, by 125 130

moving the link 27, without in any way interfering with the movement of the valves up and down with the receptacles to which they are attached. To operate the inlet controlling valve, a link 29 pivoted at one end, at 30, to the valve 12, is pivoted at the other end to an extension of the link 20. It will now be apparent that when the link 20 is drawn to the left (as viewed in Fig. 1) the valve 30 will be drawn to the left and close the inlet to the receptacle B. This same movement, however, will force the link 24 to the left and cause the valve 13 to move to uncover the exit of receptacle B, while the valve 14 will close the exit of receptacle C. A movement of the link 20 in the opposite direction will operate to close the inlet to receptacle C and open that to receptacle B and also open the exit to the receptacle C and close that of the receptacle B.

A tripping mechanism for throwing the valves into operation according to the amount of material in a receptacle, is provided, and in the apparatus shown, is as follows:—An arm 31 is pivoted to the frame at 32 and is normally held in an elevated position by a spring 33. Fixed to the arm 31 so as to turn with it about the pivotal axis 32, is an arm 34 which is pivoted to a link 35. The link 35 is in turn pivoted at 36 to an angular arm 37, which is pivoted to the frame, or an extension thereof, at 38. The end 39 of the arm 37 is adapted to be raised and lowered by thrusts or pulls upon the link 35 to control the operation of the inlet and exit valves of the receptacles and also the operation of the pump for supplying the fluid, as will be hereinafter more particularly referred to. The extremity 39 is of peculiar construction, in order to enable it to perform its function. This construction is shown on an enlarged scale and more in detail in Figs. 6, 7 and 8. Referring more particularly to these figures, the arm 37 is pivoted to the frame at 38 through the instrumentality of an offsetting arm 40 fixed to the frame. To the end of the arm 37 is fixed an arm 41 which provides an offset in which a dog 42 may turn on its pivot 43 in the end of the arm 37. This dog has its outer and lower edge cut back at an angle, as shown at 44, and is pressed outwardly by a spring 45. This construction permits a give of the dog, so that it will be pressed tightly against a co-operative clutch latch, to be hereinafter described, without requiring nicety of adjustment. Also it will enable the dog to give and the latch to slip above the dog, provided the latch should be in the way when the end 39 of the arm 37 is lowered. The arm 31 is depressed by the ear 46 or 47 attached to the receptacles B and C abutting the arm in the downward travel of either receptacle and the downward movement of the arm is accompanied by an up-

ward movement of the end 39 of the arm 37, which unlatches the clutch.

The driving and controlling means of the receptacle valves and of the pump, will now be described. The gear 18 is fixed upon the counter-shaft H, upon which also is fixed a disk 48. The counter-shaft is suitably journaled in the frame. Meshing with the gear 18 is a gear 49, upon the shaft K. This gear, when unclutched, is free to turn upon the shaft K, but is held against longitudinal movement thereon. Fixed to this gear 49 is a clutch member 50 adapted to co-operate with the clutch member 51 which is fixed against turning on the shaft K, but is slidable longitudinally thereon. A spring 52 tends to force the clutch member 51 into engagement with the clutch member 50. When so engaged, the gear 49 is driven with the shaft and turns the gear 18.

The member 51 has a circular groove 53 within which a latch 54 may enter to move the clutch member longitudinally, but which will not interfere with its rotation. The latch 54 is slidably mounted on the yoke 55 which is pivoted to the frame at 56. The arrangement of the latch is shown more in detail and on an enlarged scale in Figs. 9 and 10. The latch 54 is secured to the yoke, but permitted to slide thereon by means of the headed studs 55' and 56' which project through the slots 57 and 58, the studs being fixed to the yoke. The lower end of the latch 59 is adapted to fit into the groove 53 in the clutch member 100 and a spring 60 presses the latch downwardly. Projecting from the latch member 54 is the nose 61, the bottom face of which is horizontal, but the upper side is slanted back, as shown. This nose is adapted to hook over the dog 42 at the extremity of the arm 37, so that when this dog is elevated by the depression of one of the receptacles B or C as above described, the latch 54 will be lifted out of the groove in 110 the clutch member 51. That member will then be thrown by the spring 52 into engagement with the other member and the gearing placed in driving connection with the shaft K. The slanted upper surface of the nose 61 permits the extremity 39 to move downwardly with facility, even though the nose may be in the path of its movement. The spring 62 is interposed between the yoke 55 and the frame and tends 115 to force the yoke toward the gearing and nose 61 away from the dog 42. On the back of the yoke 55 is a bracket 63 within which is rotatably mounted a roller 64. This roller is adapted to ride upon projections 65 and 66, located upon the gear 18 on opposite sides thereof. As the roller rides upon one of these projections or cams, the yoke 54 is thrown to the left (as viewed in Fig. 4) so that the nose 61 overlaps the 120

dog 42. When the roller rolls off of the projection, the spring 62 forces the yoke toward the right. The roller 64 and the slanting surface of the projection on the gear wheel whereby the roller mounts upon the projection, is illustrated on an enlarged scale in Fig. 14.

Extending from the disk 48 to which it is pivoted, is a driving rod 67, which is pivoted at 68 to the piston rod 69 of the pump N. This pump is a suitable duplex pump and it will be apparent that for each half revolution of the disk 48, one stroke of the pump will be effected. In one side of the disk or wheel 48 is a V-shaped notch 70 having a relatively long incline 71 upon one side, thus causing a bump or cam surface 72 upon the periphery of the disk. Rolling upon the periphery of the disk is a roller 73 rotatably mounted upon a slide 74 in a fixed bracket 75. A spring 76 interposed between the bracket and the slide forces the roller against the periphery of the wheel. As the disk 48 revolves, the roller 73 will ride upon the bump 72, the spring 76 will be compressed and as the roller passes the shoulder 77, on the high side of the notch, the spring will force the roller against the incline 71, which will tend to turn the disk, until the roller reaches the bottom of the notch. It will then take considerable force to dislodge the roller from the notch, with the result that the disk will be held in a fixed position, unless a considerable force applied with the determination to move it, is exerted. There is a notch, as described, on each of the opposite sides of the disk 48. The object of having the spring and roller complete the movement of the disk and hold it firmly in position after its movement is completed, is for the purpose of insuring that the members of the clutch G will be moved beyond all possibility of accidental engagement and will be so held, so long as it is desired to keep the clutch open. The long inclines, as 71, on the sides of the notches, are so located with relation to the cams or projections 65 and 66, upon the gear 18, that the roller 73 will occupy the position as shown in dotted lines in Fig. 15 (that is, just starting down the incline) just before the roller 64 has mounted to the top of its projection on the gear, as indicated in Fig. 14, and the clutch is so adjusted, that in this position of the parts, the clutch members will be just disengaged. This being the case, the pressure of the roller 73 upon the incline 71 of the notch in the disk 48 will turn the shaft H with the gear 18, so that the roller 64 will ride to the top of the projection on the gear wheel, thereby disengaging the clutch members and they will be so held by the engagement of the roller in the V notch. With-

out such a provision, the gear wheel and its shaft H would stop as soon as the clutch members barely cleared each other, so that the driving connection was broken, and they might accidentally engage again sufficiently to throw the machine out of proper operation. With the provision, as described, however, the clutch is surely unlocked and is so held until it is desired that it shall be engaged.

The operation of the apparatus may be traced as follows:

With the receptacles both elevated, if power is supplied to the pulley wheel L and material placed in the hopper A, one of the receptacles will begin to fill, and when it has attained a weight sufficient to overbalance the counter-balancing weight, it will sink and depress the arm 31. This will elevate the extremity 39 of the arm 37. At this time the roller 64 will be upon the top of one of the projections 65 or 66, the yoke 55 will be thrown to the left (Fig. 4) so that the nose 61 will engage the dog 42. The latch 54 will then be within the circular groove 53 of the clutch member 51, so that this clutch member will be out of engagement with its coöperating member, the gear 49 will not turn with the shaft K, the gear 18 will be motionless and will be held in such position by reason of the roller 64 resting in the bottom of the V slot in the disk 48. When the arm carrying the dog 42 rises, however, in response to the sinking of one of the receptacles, the latch 54 will be elevated by the nose 61 out of the groove 53. Clutch member 51 will then be forced to the right (Fig. 4) by the spring 62, into engagement with the member 50, when the gear 49 will be locked to the shaft K. The gear H will then revolve, driving the pump and also the link 19 for operating the controlling valves for the receptacles. As soon as the gear 18 has moved through a few degrees, the roller 64 will roll off the cam on the gear 18 when the yoke 55 will be forced to the right by the spring 62 and the latch 54 will snap into the groove 53 in the clutch member. When the gear 18 has made substantially a half revolution, however, the roller 64 will ride upon the other projection on the other side of the gear wheel, and the yoke 55 will thereby be forced to the left (Fig. 4) carrying the clutch member 51 with it, the clutch being disengaged just before the roller 64 reaches the top of the projection, as has been before described. The roller 73 and spring 76 then come into play upon the incline 71 of the notch in the wheel 48 and complete the movement of the gear 18 and move the clutch member 51 out of any possibility of accidental engagement, and the nose 61 then overlaps the dog 42 in readiness to be lifted again by the dog 42 in response to the sinking of one of the receptacles.

While the invention has been illustrated in what is considered its best application, it may have other embodiments, without departing from its spirit, and is therefore not limited to the construction shown in the drawings.

What I claim is:

1. Means for supplying material comprising a movable receptacle for said material, means for opposing the movement of said receptacle under the weight of material therein, means for controlling exit of material from said receptacle, continuously running driving means for operating the said controlling means, and means controlled by the movement of said receptacle for connecting the exit controlling means in driving relation to said driving means.

2. Means for supplying material, comprising a plurality of receptacles for said material, each of said receptacles movable under the weight of material supplied thereto, means opposing such movement of the receptacle, valves controlling the inlets and exits of said receptacles, the inlet of one being closed when the other is opened, the exit of one being closed when the other is opened and the inlet of each being closed when its exit is opened, a continuously operating driving means, a clutch for connecting said driving means with the inlet and exit controlling valves, and means operated by the movement of said receptacles for controlling said clutch.

3. Means for supplying material, comprising a plurality of receptacles for said material, valves controlling the inlets and exits of said receptacles, the inlet of one being closed when the other is opened, the exit of one being closed when the other is opened and the inlet of each being closed when its exit is opened, a continuously operating driving means, a clutch for connecting said driving means with the inlet and exit controlling valves, and means operated by the amount of material in said receptacles for controlling said clutch.

4. In a mixing apparatus, the combination with a moving receptacle for delivering

granular material to the mixture, of a pump 50 for delivering fluid material to said mixture, means for opposing movement of said receptacle under the weight of material in it, means for controlling the exit of material from said receptacle, continuously operating 55 means for driving said pump and said exit controlling means, means including a clutch for operatively connecting said pump and exit controlling means with said driving means, and means operated by the movement of said receptacle for operating said clutch.

5. In a mixing apparatus, the combination with a movable receptacle for delivering granular material to the mixture, of a pump 60 for delivering fluid material to the mixture, means for opposing movement of the receptacle under the weight of material in it, valve mechanism for controlling the exit of material from said receptacle, valve mechanism 65 for controlling the inlet of material to said receptacle, continuously operating means for driving said pump and said valve mechanisms, operating connections for said valve mechanisms, operating connections for 70 said pump, a clutch for connecting said operating connections with said driving means, and means operated by said receptacle for operating said clutch.

6. In a material supplying apparatus, the combination with a plurality of individually movable receptacles for supplying a granular ingredient to a mixture, a pump for supplying a fluid ingredient to said mixture therefor, valve mechanism controlling said 85 receptacles to alternately charge and discharge the same, means for driving said valve mechanism and pump, and means operated by the weight of material in one receptacle to connect said valve mechanism and said 90 pump with said driving means.

Signed at Fremont, in the county of Dodge and State of Nebraska, this 27th day of April A. D. 1914.

WILLIAM B. NEWLON.
